(57) **CLAIM**

The ornamental design for a slow feed bowl with round exterior, as shown and described.

DESCRIPTION

FIG. 1 is an isometric perspective view of a slow feed bowl with round exterior in accordance with our design;

FIG. 2 is a front elevation view of the slow feed bowl with round exterior; the left side elevation view, the right side elevation view, and the rear elevation view all being identical to the front elevation view of the slow feed bowl with round exterior;

FIG. 3 is a top, plan view of the slow feed bowl with round exterior;

FIG. 4 is a bottom, plan view of the slow feed bowl with round exterior;

FIG. 5 is a cross-section taken along line 5-5 of FIG. 3; FIG. 6 is a cross-section taken along line 6-6 of FIG. 3; FIG. 7 is a top perspective view of the slow feed bowl with round exterior; and,

FIG. 8 is a top perspective view of the slow feed bowl with round exterior in use.

The broken lines illustrate portions of the environment of the slow feed bowl with round exterior which form no part of the claimed design.
